UNITED STATES PATENT OFFICE.

CHARLES W. YERGER, OF MILWAUKEE, WISCONSIN, ASSIGNOR TO THE CUTLER-HAMMER MFG. CO., OF MILWAUKEE, WISCONSIN, A CORPORATION OF WISCONSIN.

MOTOR-CONTROLLER.

1,225,096.

Specification of Letters Patent.

Patented May 8, 1917.

Application filed October 28, 1913. Serial No. 797,876.

To all whom it may concern:

Be it known that I, CHARLES W. YERGER, a citizen of the United States, residing at Milwaukee, in the county of Milwaukee and State of Wisconsin, have invented new and useful Improvements in Motor-Controllers, of which the following is a full, clear, concise, and exact description, reference being had to the accompanying drawing, forming a part of this specification.

My invention relates to improvements in motor controllers.

It may be advantageously used in various different relations and particularly in connection with electric elevators.

In elevator service it is highly desirable to provide for gradual and smooth acceleration and deceleration but much difficulty has been experienced in this connection. For example, the back lash or lost motion in the gearing, the wide variations in load and the establishment of dynamic braking connections have all given much trouble in this connection.

My invention has among its objects to provide a controller for the aforesaid and other classes of machinery where the foregoing or similar conditions are met with which will provide for much smoother acceleration and deceleration than has heretofore been attained.

Various other objects and advantages will hereinafter appear.

For the purpose of more fully disclosing the nature and advantages of my invention, I have illustrated in the accompanying drawing a very simple embodiment thereof which I shall now describe.

The controller is shown as applied to a compound motor 1 having an armature A, a series field winding F and a shunt field winding F'. It should, of course, be understood that it might be applied to any other preferred type of motor.

The controller includes an electro-responsive main line switch 2, electro-responsive accelerating switches 3, 4 and 5 and an electro-responsive armature shunt switch 6 which normally stands in closed position.

The switches 3, 4 and 5 control resistances r , r' and r^2 in series with the motor, and are governed by series relay switches 7, 8 and 9 respectively. The armature shunt controlled by the switch 6 includes a resistance r^3 .

The operating windings of the switches 2,

3, 4, 5 and 6 are controlled by a master switch 10 and certain interlocking contacts hereinafter specified.

Briefly set forth, the controller functions as follows:

It starts the motor with both the series resistances r , r' and r^2 and the armature shunt resistance r^3 included in circuit. The armature shunt resistance is manually controlled and may be left in circuit as long as desired but must be disconnected before the switches 3, 4 and 5 can respond. Further, as will hereinafter appear, provision is made whereby the armature shunt is necessarily maintained for a temporary period after starting. When the switch 6 responds to open the armature shunt then the switches 3, 4 and 5 respond automatically and successively to accelerate the motor, subject to retardation by the series relay switches. For deceleration the resistance r^3 is first connected across the motor armature by the switch 6 after which the switches 3, 4 and 5 are deenergized successively to reinsert the series resistance. Thereafter, the main line switch 2 is opened to disconnect the motor from circuit leaving the shunt around the armature whereby the motor acts as a dynamic brake. Thus provision is made for shunting the motor armature through the resistance r^3 for starting and for insuring interruption of the armature shunt prior to removal of any of the series resistance, whereas in stopping the resistance r^3 is connected in shunt with the motor armature before any of the series resistance is reinserted in circuit.

The inclusion of the shunt resistance r^3 in starting insures initial speed and torque of a very low value whereby any back lash or lost motion in the gearing may be readily taken up without shock or jar to the driven machinery. Also, the shunt resistance performs another very important function, especially in connection with controllers governed by the speed or electrical conditions of the motor, in that it compensates for variations in load to prevent unduly abrupt acceleration. As is well understood, such types of controllers are adjusted for maximum load starting whereby if the load is light there is a tendency for an exceedingly abrupt acceleration. This, however, is prevented by the shunt resistance which insures low speed and low torque for at least a

temporary period, irrespective of the load conditions and accordingly insures a gradual and smooth initial start. On the other hand, the armature shunt in no wise interferes with the operation of the controller under heavy loads since if the motor fails to start said shunt may be interrupted after a short interval by operation of the master controller.

10 Reverting now to the deceleration operation, it will be observed that inasmuch as the resistance r^3 is connected in shunt with the motor armature while all of the series resistance is excluded it will have absolutely no effect on the speed of the motor. However, upon the reinsertion of the series resistance it aids materially in slowing down the motor and in producing a uniform deceleration. Thus the difficulties heretofore met with in the establishment of an armature shunt for gradual slow down are entirely eliminated and the shunt used to great advantage in deceleration.

15 The controller and its circuit connections will now be more specifically described. The master switch is provided with contact fingers 11, 12 and 13 and with electrically connected cooperating segments 11^a, 12^a and 13^a. In its first operative position 20 it bridges contacts 11 and 12 by segments 11^a and 12^a and in its second position bridges contacts 11 and 13 by segments 11^a and 13^a.

25 In its first position the master switch closes circuit from line L by conductor 14 through the winding of switch 2 by conductor 15 to contact finger 12 and thence to finger 11 by conductor 18 to line L'. Switch 2 thereupon responds to complete the motor circuit.

30 35 The motor circuit may then be traced from line L through switch 2, by conductor 19 through the operating winding of relay 7, by conductor 20 through the resistances r , r' and r^3 and thence through the series field winding F and motor armature A, by conductor 21 to line L'. The shunt field winding F' of the motor is permanently connected from line L by conductor 22 through said winding to line L'. Under 40 these conditions circuit is also closed from one terminal of the motor armature by conductors 21 and 23 through normally closed switch 6, by conductor 24 through resistance r^2 , by conductor 25 to the opposite terminal 45 of the motor armature. These connections are maintained until further operation of the master switch.

45 When the master switch is moved to its second position it completes the energizing circuit of switch 6. This circuit may be traced from line L through switch 2 by conductors 18 and 26 through the winding of switch 6, by conductor 27 to contact finger 13 and thence to contact finger 11 and to line L'. Switch 6 thereupon responds to

50 open the resistance shunt around the motor armature. In this connection, it should be noted that switch 6 cannot respond until switch 2 closes and until the master switch is thrown to full "on" position. Accordingly, a time element is provided whereby the retention of the shunt is insured for at least a temporary period. Of course, in practice, the time element may be varied in numerous different ways to insure retention of the shunt for any predetermined minimum period.

55 Switch 6 upon responding completes the energizing circuit of the accelerating switch 3 through auxiliary contacts 30. This circuit may be traced from conductor 26 through said auxiliary contacts by conductor 31 through the relay switch 7 and thence through the operating winding of switch 3 by conductors 32 and 18 to line L'. Switch 3 thereupon responds subject to retardation by the relay 7 and upon responding varies the motor connection. The motor circuit then extends from conductor 19 by conductor 33 through switch 3, by conductor 34 through the operating winding of relay 8 by conductor 36 to and through resistance r' , etc. Switch 3 upon responding also completes, through auxiliary contacts 3^a, the circuit of the winding of switch 4. This circuit extends from conductor 33 through said auxiliary contacts, by conductor 37 through relay switch 8 and thence through the winding of switch 4 by conductor 38 to conductor 32.

60 Switch 4 thereupon responds subject to retardation by relay 8. The motor circuit then extends from conductor 34 by conductor 39 through said switch 4, by conductor 40 through the winding of relay 9, by conductor 41 to and through resistance r^2 , etc. Switch 4 upon closing also completes a circuit from conductor 38 through its auxiliary contacts 4^a, by conductor 42 through relay switch 9 and thence through the operating winding of switch 5, by conductor 43 to conductor 32.

65 Switch 5 thereupon responds subject to retardation by relay 9, connects conductor 40 by conductor 44 to the motor armature. This excludes from circuit all of the series resistance and also the series field winding.

70 When the master switch is moved toward off position it first deenergizes switch 6 which drops out to reclose the circuit of resistance r^3 across the armature A. Switch 6 upon dropping out also deenergizes switches 3, 4 and 5 which thereupon open successively and reinsert the series resistances r , r' and r^2 in circuit. Then when the master switch is moved to off position it deenergizes main switch 2, thereby disconnecting the motor from circuit. This leaves the motor with its armature shunted by resistance r^3 for dynamic braking.

What I claim as new and desire to secure by Letters Patent is:

1. In a motor controller, in combination, means for establishing power connections, accelerating means, means to normally shunt the motor armature and means necessitating operation of the first means to establish power connections prior to operation of the third means to interrupt the armature shunt and necessitating such operation of said shunting means prior to operation of said accelerating means. 65
2. In a motor controller, in combination, means for establishing power connections, automatic accelerating means, means to normally shunt the motor armature and to control said accelerating means to insure against operation thereof pending interruption of the armature shunt and means insuring retention of said armature shunting means in normal position during establishment of power connections and for a temporary period thereafter. 70
3. In a motor controller, in combination, means for establishing power connections, means to normally shunt the motor armature, automatic accelerating means dependent for operation upon prior operation of said second means to interrupt the armature shunt and manual control means for said first two mentioned means insuring maintenance of the armature shunt during establishment of power connections and for a temporary period thereafter variable at will. 75
4. In a motor controller, the combination with electro-responsive means for establishing power connections and increasing the power supply for accelerating the motor, of electro-responsive means normally completing an armature shunt and control connections for both of said means insuring retention of the armature shunt for a temporary period following establishment of power connections and necessitating interruption of the armature shunt prior to any increase in the power supply. 80
5. In a motor controller, the combination with electro-responsive means for establishing power connections for the motor and increasing the supply of power subject to the electrical conditions in the motor circuit, of means normally completing a shunt around the motor armature and insuring against response of said first mentioned means to increase the power supply until after interruption of the armature shunt. 85
6. In a motor controller, in combination, means for controlling the continuity of the motor circuit, means for completing an armature shunt for the motor upon initial 90
- closure of the motor circuit and a series relay power controller for accelerating the motor but only after previous operation of said second mentioned means to interrupt the armature shunt. 95
7. In a motor controller, the combination with electro-responsive means controlling a shunt for the motor armature, of electro-responsive means for controlling the power supplied to the motor, and means for directing the operation of said former means to slow down the motor, said first mentioned means operating to complete the armature shunt prior to any reduction in the power supplied to the motor. 100
8. In a controller for electric motors, in combination, means controlling the power connections for the motor and varying the power supplied for both acceleration and deceleration, of means normally completing a shunt for the motor armature and acting to interrupt said shunt prior to any increase in power for acceleration and to reestablish said shunt prior to any decrease in power for deceleration. 105
9. The method of controlling an electric motor with an armature shunt resistance, and a series resistance consisting in starting with both resistances connected in circuit, progressively, interrupting the armature shunt and gradually excluding the series resistance for acceleration and progressively reestablishing the armature shunt and gradually including the series resistance for deceleration. 110
10. The method of decelerating an electric motor consisting in first shunting the motor armature with all series resistance excluded from the armature circuit to minimize the effect of the shunt and second inserting resistance in the armature circuit while maintaining power connections to increase the slow-down effect of the armature shunt. 115
11. The method of decelerating an electric motor consisting in shunting its armature with all series resistance excluded from the armature circuit to initially minimize the effect of the shunt and in thereafter inserting resistance in series with the motor armature while maintaining power connections and a constant value of the armature shunt to thereby increase the slow-down effect of said shunt. 120

In witness whereof, I have hereunto subscribed my name in the presence of two witnesses.
